UNITED STATES PATENT OFFICE

108,273

DESIGN FOR A FILE TRAY

Enoch R. Winstrom, Long Beach, Calif.

Application July 21, 1937, Serial No. 70,569

Term of patent 14 years

To all whom it may concern:

Be it known that I, Enoch R. Winstrom, a citizen of the United States, residing at Long Beach, in the county of Los Angeles and State of California, have invented a new, original, and ornamental Design for a File Tray, of which the following is a specification, reference being had to the accompanying drawing, forming a part thereof.

I claim:

The ornamental design for a file tray as shown.

ENOCH R. WINSTROM.
